UNITED STATES PATENT OFFICE.

JOHN LESLIE CLOUDSLEY, OF LONDON, ENGLAND.

VALVE FOR INTERNAL-COMBUSTION ENGINES.

1,178,495.

Specification of Letters Patent.

Patented Apr. 11, 1916.

Application filed April 8, 1915. Serial No. 19,939.

To all whom it may concern:

Be it known that I, JOHN LESLIE CLOUDSLEY, a subject of the King of England, residing in London, England, have invented 5 certain new and useful Improvements in Valves for Internal-Combustion Engines, of which the following is a specification.

This invention is for improvements in or relating to valves for internal combustion engines and has for its object to provide an improved construction of valve whereby both the gas and the air are controlled by separate throttles so as to insure the mixture being correct at all speeds and loads.

15 It will be understood that where gas is referred to in this specification, it may mean either true gas as used in a gas engine, atomized liquid fuel, or richly carbureted air.

The invention is applied to engines having 20 separate chambers or pumps from which air and gas are separately supplied to the working cylinder.

The present invention therefore consists in the combination, in an internal combustion 25 engine having separate gas and air inlets and a throttle valve on each inlet, with the valves of means whereby the variation in pressure produced in the conduit on the delivery side of one valve by hand or governor operation 30 thereof, controls the movement of the other valve, for example in such a manner that the pressure on the delivery side of the second valve becomes equal to that on the delivery side of the first valve.

35 In the preferred construction the air-valve is automatically controlled by the variations in pressure in the passage on the engine side of the gas-throttle. The means for effecting this may comprise a piston or dia- 40 phragm subjected differentially to the pressures in the passages on the engine side of the two valves respectively; the piston or diaphragm may be arranged in a cylinder whereof one side is open to the passage on 45 the engine side of the air-valve and the other end of the cylinder is connected by an open pipe to the engine side of the gas-throttle.

According to another feature of the invention an auxiliary air-valve may be pro- 50 vided to admit air into the gas-pipe on the engine side of the gas-throttle, this valve being operatively connected to the gas-throt- 55 tle in such a manner that it is open when the gas-throttle is closed and vice versa. It will be appreciated that the opening or clos- 60

gas-pipe and this variation in pressure also has an effect on the main air-valve. This arrangement is designed to provide in the manner hereinafter described for the variation in the strength of the mixture of the combustible charge which is required under ordinary conditions; these conditions are that when the engine is throttled down on light load, only a weak mixture is necessary, 65 but when the gas-throttle is fully open and the engine is under load a stronger mixture is required.

Other features of the invention are herein- 70 after described and the novel details set forth in the claims.

The accompanying drawing shows in sec- 75 tional elevation a gas-valve and an air- valve for a two-cylinder engine, adapted to co-operate with one another in the manner above described. It will be understood that the relative positions of these two valves will not necessarily be the same as indicated for they will be situated at any convenient place on the engine. The construction illus- 80 trated is further adapted for control by an engine governor to maintain the engine at a uniform speed.

The gas-throttle A is situated in the gas- 85 inlet-pipe A¹ which communicates with two pipes A² A³ leading to each of the cylinders of a two-cylinder engine. The throttle A it- 90 self may take any convenient form; in the construction illustrated it comprises a slotted cylinder which is movable axially across the supply pipe A¹ to present a vari- 95 able aperture thereto and thereby control the quantity of gas flowing through it to the engine, or to the pump supplying the engine. From the pipe A⁴ on the engine-side of the throttle A, connection is made by a tube B to a chamber C so that variations in the pres- 100 sure of the gas in A⁴ are communicated to the chamber C. This chamber, which is constructed as a cylinder contains a piston C¹ which is connected to a valve D which controls the main air supply to the engine. In the particular construction illustrated the chamber C is formed integral with the valve-chamber D¹ for the valve D and an air inlet D² is situated in one wall of the chamber D¹. Two outlets D³, D⁴ respec- 105 tively communicate with the crank-chambers of the two cylinders. The piston C¹ is, with this arrangement, exposed on one side to the pressure in the chamber C. (that is to say 110 to the pressure in the tube A⁴) and on the

other side to the pressure in the valve-chamber D^1 and passages D^3 , D^4 (that is to say, the pressure of the main air supply on the engine side of the valve controlling that supply). The valve D may be of any desired form and is illustrated as a sleeve secured on the rod C^2 by a grub-screw C^3 ; this sleeve moves across the inlet aperture D^2 uncovering more or less of it as the piston 10 C^1 moves.

While the gas-throttle A may be controlled by hand, in the construction illustrated it is controlled by an engine governor. A lever E pivoted at E^1 on a bracket secured 15 to the engine frame is operatively connected, at one end, (not shown) to the governor gear and at the other end, by an adjustable tie-rod E^2 , to the throttle, the arrangement being such that when the engine speed rises the 20 valve A is moved toward its closing position.

An auxiliary air-valve G is provided opening into the pipe A^4 . This valve has to deal with only comparatively small quantities of air and is preferably a needle-valve. 25 It is operatively connected with the gas-throttle A but so as to be moved in the opposite direction; that is to say when the gas-throttle is moved toward its closing position the auxiliary air-valve G is moved toward 30 its open position. The throttle G is connected by a tie-rod F to a lever F^1 pivoted at F^2 and this lever is connected on the opposite side of the pivot F^2 by an adjustable tie-rod F^3 to the lever E. It will be seen that 35 when the lever E moves the valve A, it simultaneously rocks the lever F^1 and thereby moves the valve G in the opposite direction to the movement of the valve A.

The control of the engine is effected by the 40 valves hereinbefore described in the following manner: If the engine is running on load, and the load is removed the speed rises and the governor thereupon moves the gas-throttle A toward its closing position. The 45 throttling of the gas supply produces a diminished pressure in the part A^4 of the inlet-pipe and this reduced pressure is communicated through the pipe B to the chamber C of the air-controlling valve D. The 50 pressure on the lower side of the piston C^1 being reduced causes the piston to fall and move the main air-valve D downward across the air-inlet D^2 thus throttling the air supply. This movement continues until the 55 throttling of the air supply is such that the pressure in the chamber D^1 and pipes D^3 , D^4 is the same as the pressure in the chamber C. The arrangement and adjustment of the parts are such that the throttling of the air- 60 supply is proportional to the throttling of the gas-supply so that with these parts only in operation a mixture of constant strength would be obtained. The auxiliary air-valve G however, which admits air to the gas pipe 65 A^4 is, as above mentioned, operated simul-

taaneously with the gas-valve A. When, therefore, the gas-valve A is moved toward its closing position the auxiliary air-valve G is opened and some air is admitted to the pipe A^4 . This admission of air prevents the 70 full reduction of pressure, which would have been obtained by the throttling action of the valve A from being obtained and consequently the piston C and valve D are not moved to the full extent which they would 75 have been consequent on the change in pressure of the gas alone. A proportionately greater quantity of air is thereby allowed to enter at the air-inlet D^2 and this, together with the small quantity of air which enters 80 past the valve G, gives a weaker mixture which is what is required when the engine is running light.

It will be seen that this invention makes use of the slight increase in the engine speed 85 by the action of the governor, to effect the change in the strength of the mixture which is desirable with load variations. The operation of these valves has been described for changes due to taking the load off the 90 engine and it will be appreciated that the converse action of putting load on the engine causes a reduction in speed, and the operation of the valves is then such as to give a greater quantity of a stronger mix- 95

This invention, it will be seen, provides a means for automatically controlling both the quantity of fuel supplied to the engine, and the richness of the mixture according 100 to the conditions of load and speed under which the engine is running.

Various modifications may be made in the details of the invention without departing from the spirit thereof; thus for example, 105 the arrangement above described may be reversed in so far as the primary control may be effected on the air-valve and the automatic control on the gas-throttle.

The valves hereinbefore described are 110 particularly suitable for use with a governor-controlled engine but it will be appreciated that they may also be used with a hand-controlled engine.

What I claim as my invention and desire 115 to secure by Letters Patent is:—

1. In an internal combustion engine the combination of a gas-inlet, a throttle controlling said inlet, a separate air-inlet, an air-valve controlling said inlet and means 120 subjected differentially to the pressures in the conduits on the delivery side of the valves controlling said inlets, said means controlling one of said valves.

2. In an internal combustion engine the 125 combination of a gas-inlet, a throttle controlling said inlet, a separate air-inlet, an air-valve controlling said inlet, a rod carrying said air-valve and extending into a cylinder, a piston mounted on said rod and op- 130

erative in said cylinder, a conduit connecting one end of said cylinder to the air-inlet conduit on the delivery side of the air-valve and another conduit connecting the other 5 end of said cylinder to the separate gas-inlet on the delivery side of the gas-throttle, substantially as set forth.

3. In an internal combustion engine the combination of a gas-inlet, a throttle controlling said inlet, a separate air-inlet, an air-valve controlling said inlet, means controlled by the variations in pressure in the conduit on the delivery side of one of said valves, operative to control movements of 10 the other of said valves, an auxiliary air-inlet communicating with the gas-inlet on the delivery side of the gas-throttle and a valve controlling said auxiliary air-inlet and operatively connected to the throttle, sub- 15 substantially as set forth.

4. In an internal combustion engine the combination of a gas-inlet, a throttle controlling said inlet, a separate air-inlet, an air-valve controlling said inlet and means subjected differentially to the pressures in 25 the conduits on the delivery side of the valves controlling said inlets, said means controlling one of said valves, an auxiliary air-inlet communicating with the gas-inlet on the delivery side of the gas-throttle and 30 a valve controlling said auxiliary air-inlet and operatively connected to the throttle, substantially as set forth.

In testimony whereof I have signed my name to this specification in the presence 35 of two subscribing witnesses.

JOHN LESLIE CLOUDSLEY.
